PROCESS AND APPARATUS FOR UTILIZING THE HEAT OF THE WASTE GASES OF
ALTERNATELY WORKING GAS GENERATORS AND THAT OF THE PRODUCED GAS

UNITED STATES PATENT OFFICE

ALBERT BREISIG, OF VIENNA, AUSTRIA

PROCESS AND APPARATUS FOR UTILIZING THE HEAT OF THE WASTE GASES OF ALTERNATELY-WORKING GAS GENERATORS AND THAT OF THE PRODUCED GAS

Application filed June 11, 1926, Serial No. 115,395, and in Austria June 13, 1925.

In the manufacture of water gas or of a mixture of water gas and coal (distillation) gas by means of alternately working generators, that is to say such, in the operation of 5 which a period of blowing up, called the "glow" alternates with a period of gas making, called the "run", only part of the entire amount of heat generated during the blow is accumulated in the coke and thus directly 10 utilized in the subsequent "run" so that the gases will escape from the generator with a high temperature and containing a considerable amount of heat. This surplus of heat is utilized for the generation and for the 15 superheating of the steam required in the gas making process either by burning the said gases in a heat accumulator, which then serves for generating and superheating the steam, or by leading them into a boiler constructed 20 for the utilization of waste heat. By neither of these two ways is a perfect and economical utilization of the heat possible.

As the time, during which the blowing is effected, amounts to only about one fifth of 25 the entire time of operation, waste heat boilers capable of utilizing during these short blowing periods the entire heat contained in the waste gases should have such large heating surfaces as is not practicable. If on the 30 other hand a heat accumulator is employed, in which the steam is superheated, the waste gases will escape therefrom with a considerably great content of heat, but at a temperature of about 300 to 500° C., which in the most 35 cases is too low for allowing further economical utilization thereof. The same inconvenience also arises, if the accumulator not only serves for superheating the steam, but also for generating it.

40 On the other hand this latter method has the advantage of automatically adjusting to a certain extent the amount of the generated steam according to the conditions, under which the generator works. Accumulators of 45 this kind may for instance be of the type, in which the hot gases pass through a body of superposed iron bars. The total surface and weight of this body can be chosen such that the iron bars at the given temperature and 50 speed of the gases take up just as much heat

as is required for the generation of steam during the subsequent period of "run". If under such circumstances by inadvertance of the operator or owing to an alteration of the resistances in the coke column or in the blower 55 duct an insufficient amount of air is blown in, there will be less heat accumulated in the iron body and for this reason also less steam will be generated. Consequently less steam is fed into the generator, which in such case 60 had not been heated up to an adequate that is to say regular extent, so that finally it will assume its regular temperature and in spite of the deficient operation will yield good gas. If the blowing is effected excessively, more 65 steam is generated and introduced into the generator heated up too much, so that also in this case it will reassume its regular temperature. As is seen, by the use of an 70 accumulator of the said type advantages are obtained in respect of the quality of the generated gas and in respect of fuel consumption, which advantages are not attainable by employing steam from a boiler. The admission of steam from a boiler is as a rule measured by the time of its flow, so that, if the vapor tension is constant, there is always the same amount of steam fed into the generator without any consideration of the changing 75 state of the latter. Therefore, if the temperature of the generator is too low or too high, there will no accommodation, that is to say adjustment of the amount of steam according to the temperature of the generator take place.

Consequently in aiming at a perfect utilization of the heat of the gases in question it appears desirable to assure the described automatic adjustment by maintaining the heat 80 accumulator serving as vaporizer.

According to the present invention this is obtained by leading only part of the gases, which escape from the baffle brickwork of the recuperator serving during the run for superheating the steam, into the vaporizer, 95 this part being chosen such, that it is sufficient for generating the steam required for the run, whilst the remainder of the gases in question is branched off and conducted to a waste heat boiler. Thus it is obtained, that 100

the reduced quantity of waste gases introduced into the vaporizer is cooled down to a lower temperature than had hitherto been possible and in this manner is utilized more completely, whilst on the other hand the waste heat boiler has only to take up the excess of heat over the amount required by the generator process and for the generation of the steam, and therefore can be of considerably smaller dimensions. Nevertheless its efficiency is not diminished, as the waste gases enter it with a high temperature. This advantage is not given in the known arrangement with a boiler being mounted after or behind the accumulator, as in the latter case the gases escaping from the vaporizer are cooled down to a temperature of 300° to 500° C.

In the drawing a gas generating plant adapted for carrying out the invention is illustrated by way of example.

A is the generator, into which fuel is introduced through B and air through C. The gases produced during the "blow" leave the generator through the pipe D and pass into the baffle brickwork of the recuperator E, where they are completely burnt, additional air being admitted at F. Of the hot combustion gases escaping from the baffle brick-work of the recuperator E one part enters the vaporizer G and from there passes through the opened stack valve H into the open air. The other part is through the valve J conducted into a waste heat boiler M, from which it escapes through a separate chimney T. In connection with the gate valves H and J preferably also throttle valves K and L are mounted in order to allow adjustment of the division of the gases to be divided between the vaporizer and the boiler.

During the "run" the valves J, H and the air valves are closed. Water is injected into the vaporizer at N, the generated steam is superheated by the baffle brickwork of the recuperator E and passes through the pipe D into the generator A. The generated water gas flows through the duct S into the smoke tubes R of the waste heat boiler and is from there led off to P.

Waste heat boilers as illustrated in the drawing, which are heated by the waste gases passing along and around the water tubes W as well as by the generated gas are known already. Their use in the present process involves special advantages inasmuch as the working is rendered much more regular than had hitherto been possible by the method of introducing the entire quantity of waste gases leaving the recuperator E into the boiler. In this known method of operating the periodical supply of heat by the waste gases was relatively very high in comparison with that of the heat supply by the generated water gas. The generation of steam therefore took place rather irregularly. By the

present method the amount of heat supplied by the waste gases is decreased and thus more equalled with that furnished by the generated water gas, a more uniform generation of steam being thus assured.

70

What I claim is:

1. In the operation of an alternately working gas generator combined with a heat accumulator serving during the run as vaporizer, a recuperator serving during the run for superheating the steam and a waste heat boiler for utilizing the heat of the produced gas during the run, the step which consists in simultaneously passing a part of the waste gases leaving the recuperator into the vaporizing accumulator and another part of the waste gases into the boiler.

75

2. A gas generating apparatus comprising a gas generator, a recuperator, a vaporizer, a boiler adapted to utilize heat contained in waste gases leaving the generator, a conduit connecting the generator with the recuperator, means connecting the vaporizer and boiler with the recuperator whereby the amount of gas leaving the recuperator is in part passed to the vaporizer and in part to the boiler, said means comprising valved conduits, and conduit means connecting the generator with the boiler to pass generated gas thereto.

80

In testimony whereof I have affixed my signature.
